Solomon R. Guggenheim

UNITED STATES PATENT OFFICE

2,564,353

TOOTHBRUSH CABINET WITH AGITATOR

Garlin Coleman, New York, N. Y.

Application December 23, 1949, Serial No. 134,809

7 Claims. (Cl. 312—206)

1

This invention relates to new and useful improvements in cabinets or the like for toothbrushes.

One object of the present invention is to provide a case for toothbrushes in the form of a wall cabinet of plastic which may be of a color to harmonize with the decor of the room in which the cabinet is placed and to contrast with the colors of the toothbrush or toothbrushes mounted therein and yet which is sufficiently transparent to permit viewing the contents of the cabinet without opening the door thereof.

Preferably the cabinet is mounted above a sink or the like and another object of the invention is to provide the cabinet with ventilating openings to facilitate drying of the toothbrushes therein and with drainage openings for the water which drips from said brushes after they have been used.

Still another object of the invention is to provide means actuated automatically on opening and closing the door of the cabinet to agitate the supporting means for the toothbrushes and thus to facilitate removing the moisture therefrom.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the cabinet of the invention with a toothbrush mounted therein.

Fig. 2 is a front view of the cabinet with the door open.

Fig. 3 is a fragmentary sectional view on line 3—3 of Fig. 2.

Fig. 4 is an enlarged fragmentary side view of the cabinet and illustrates one of the hinges for the door thereof and also the means for securing together the top and sides of the cabinet.

Fig. 5 is an enlarged view of the cabinet from beneath and illustrates the means for securing the bottom thereof to the sides.

Fig. 6 is an enlarged fragmentary sectional view on line 6—6 of Fig. 1.

Fig. 7 is a front view similar to Fig. 2 but illustrates a modification of the invention whereby the supporting shelf of the cabinet is agitated by opening and closing the door.

Fig. 8 is an enlarged sectional view on line 8—8 of Fig. 7.

2

Fig. 9 is a fragmentary sectional view on line 9—9 of Fig. 8.

Fig. 10 is a fragmentary sectional view on line 10—10 of Fig. 8.

Fig. 11 is an enlarged fragmentary view looking in the direction of the arrow 11 of Fig. 7.

Fig. 12 is an enlarged perspective view of the agitator mounted on the door and illustrated also in Fig. 7.

10 Fig. 13 is a face view partly broken of the inner side of the cabinet door removed from the remainder of the cabinet and illustrates an inactive position of a certain agitator mounted on the door.

15 Referring to Figs. 1 to 6, the cabinet of the invention comprises a rear wall partition 15 to which are secured by screws 16 a top partition 17, side walls 18 and a floor partition 20. The walls 18 are secured by screws 21 (Fig. 4) to the top

20 piece 17 and by screws 22 (Fig. 5) to the floor piece 20. A door 23 is pivotally secured by hinges 24 to the left-hand side wall 18 and is provided with a handle 25 secured in place by a screw 26 (see also Fig. 6). Adjacent the inner face of the

25 door 23, the handle 25 is formed with a notch 25^a engageable with a keeper projection 18^a on the side wall 18 for retaining the door 23 in a closed position, see particularly Fig. 6. The side walls 18 are provided above their centers with transverse grooves to receive the ends of, and support, a toothbrush rack or shelf 27 having therein a plurality of keyhole slots 28 for toothbrushes 30. The slots 28 are so designed that a toothbrush handle can be slid thereinto edgewise and turned so that the width of the handle is greater than the mouth of the slot, the brush then being held against becoming disengaged from the shelf 27.

30 All of the cabinet components described, with the exception of the hinges and the screws, are formed of transparent plastic suitably colored to complement the decor of the room in which the cabinet is placed and to contrast with the colors of the one or more toothbrushes suspended therein.

35 In order that the cabinet be secured on a wall or the like with a minimum of effort, the rear wall 15 thereof is provided with two upper and one lower holes 31 through which nails or screws can be driven into the wall.

40 Means are provided for ventilating the cabinet to facilitate the drying process of the toothbrushes therein, and for draining out of the cabinet the water dripping from the wet toothbrushes. The ventilating means comprises a plu-

rality of holes 32 in the upper portions of side walls 18 (Figs. 1 and 4). The drainage means comprises a plurality of holes 33 in the bottom partition 20 of the cabinet, which arrangement makes it desirable to mount the cabinet over a sink or the like.

In a modified form of the invention illustrated in Figs. 7 to 13, means are provided for automatically agitating the shelf 27 as the door 23 is opened and closed, thus quickening the drying process of the toothbrushes by shaking loose the droplets of water clinging thereto.

The modified cabinet is constructed the same as described hereinbefore except for the shelf 27 and certain additions so that a redescription of the unchanged parts is deemed unnecessary.

The shelf 27 in the modified cabinet is pivoted near its rear edge on trunnions 34 journalled in the side walls 18 (Figs. 8 and 9), the front of the shelf being supported on blocks 35 secured by screws 36 (Fig. 10) to the said side walls. The edge of shelf 27 adjacent rear wall 15 is rounded as at 37 (Fig. 10) to permit its rocking on the trunnions 34 and a leaf spring 39 secured to rear wall 15 is provided to restrain the shelf against the blocks 35.

In order to agitate the shelf in a rocking manner, an agitating member 38 (Figs. 7, 8, 12 and 13) having rack tooth-like serrations 40 on its upper edge is mounted on the door 23 and cooperates with a tooth 41 on a bracket 42 secured to the under side of shelf 27 near its forward edge by screws 43 (Figs. 7, 10 and 11). The serrated upper edge 40 of actuator 38 is arcuate as shown in Fig. 8 to insure engagement thereof with tooth 41 as the door swings on its hinges.

The construction is such that as the door 23 is swung closed the serrations will come into contact with the tooth 41 and will rock the front edge of shelf 27 forcibly upward, said shelf being rocked oppositely between serration high points by the spring 39. Thus, each time door 23 is opened or closed the shelf 27 is agitated forcibly in a rocking manner and any droplets of water clinging to the bristles of the toothbrushes supported thereon are shaken loose.

Preferably the agitator is provided at its lower end with a hole 44 (Fig. 13) through which there is frictionally passed a screw 45 to secure the same on door 23 in such manner that the agitator can be rotated about said screw through an angle of 180° to a position in which the serrations 40 thereof cannot act on the tooth 41 to rock the shelf, if it is desired temporarily to refrain from such automatic shelf agitation. This inactive position of the agitator 38 is illustrated in Fig. 14.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A wall cabinet for toothbrushes of transparent colored plastic comprising a rear wall, side walls, top and bottom partitions, a door hinged to one of said side walls, a handle for opening and closing said door, a pair of trunnions journalled one in each of said side walls above its center and close to said rear wall, a shelf pivoted on said trunnions, a plurality of keyhole slots

in said shelf to receive and support a plurality of toothbrushes, a pair of blocks secured one to each of said side walls to support the forward portion of said shelf, a spring to tension said shelf against said blocks, and means on said door and engaging said shelf to act automatically on opening and closing said door to rock said shelf against the tension of said spring to shake loose any droplets of water clinging to said toothbrushes.

2. A wall cabinet for toothbrushes of transparent colored plastic comprising a rear wall, side walls, top and bottom partitions, a door hinged to one of said side walls, a handle for opening and closing said door, a pair of trunnions journalled one in each of said side walls above its center and close to said rear wall, a shelf pivoted on said trunnions, a plurality of keyhole slots in said shelf to receive and support a plurality of toothbrushes, a pair of blocks secured one to each of said side walls to support the forward portion of said shelf, a spring to tension said shelf against said blocks, means acting automatically on opening and closing said door to rock said shelf against the tension of said spring to shake loose any droplets of water clinging to said toothbrushes, said means comprising an agitator mounted on said door and including a serrated upper edge, and a bracket including a tooth engaged by said serrated edge secured to the under side of said shelf near its forward edge, the serrations acting through said tooth to rock the front edge of the shelf upward, and the spring rocking the shelf downward.

3. A wall cabinet for toothbrushes of transparent colored plastic comprising a rear wall, side walls, top and bottom partitions, a door hinged to one of said side walls, a handle for opening and closing said door, a pair of trunnions journalled one in each of said side walls above its center and close to said rear wall, a shelf pivoted on said trunnions, a plurality of keyhole slots in said shelf to receive and support a plurality of toothbrushes, a pair of blocks secured one to each of said side walls to support the forward portion of said shelf, a spring to tension said shelf against said blocks, and a pivotally mounted means on said door and engaging said shelf to act automatically on opening and closing said door to rock said shelf against the tension of said spring to shake loose any droplets of water clinging to said toothbrushes.

4. A wall cabinet for toothbrushes of transparent colored plastic comprising a rear wall, side walls, top and bottom partitions, a door hinged to one of said side walls, a handle for opening and closing said door, a pair of trunnions journalled one in each of said side walls above its center and close to said rear wall, a shelf pivoted on said trunnions, a plurality of keyhole slots in said shelf to receive and support a plurality of toothbrushes, a pair of blocks secured one to each of said side walls to support the forward portion of said shelf, a spring to tension said shelf against said blocks, and means acting automatically on opening and closing said door to rock said shelf against the tension of said spring to shake loose any droplets of water clinging to said toothbrushes, said means comprising an agitator mounted on said door and including a serrated upper edge, and a bracket including a tooth engaged by said serrated edge secured to the under side of said shelf near its forward edge, the serrations act-

ing through said tooth to rock the front edge of the shelf upward, and the spring rocking the shelf downward, said agitator being swingable manually to a position in which said serrations do not act on said tooth.

5. A wall cabinet for toothbrushes of transparent colored plastic comprising a rear wall, side walls, top and bottom partitions, a door hinged to one of said side walls, a handle for opening and closing said door, a pair of trunnions journaled one in each of said side walls above its center and close to said rear wall, a shelf pivoted on said trunnions, a plurality of key-hole slots in said shelf to receive and support a plurality of toothbrushes, a pair of blocks secured one to each of said side walls to support the forward portion of said shelf, a spring to tension said shelf against said blocks, and means acting automatically on opening and closing said door to rock said shelf against the tension of said spring to shake loose any droplets of water clinging to said toothbrushes, said means comprising an agitator pivotally mounted on said door and including a serrated upper edge, and a bracket including a tooth engaged by said serrated edge secured to the under side of said shelf near its forward edge, said agitator being pivotal to a position in which the serrations coact with said tooth to rock the front edge of the shelf upward, the spring restoring said shelf, or to a position in which said serrations do not coact with said tooth.

6. A wall cabinet for toothbrushes, comprising a cabinet body having spaced side walls and an open front side, a door hinged to one of said side walls to swing on a vertical axis for closing the open front side, a pair of end aligned trunnions journaled one in each of said side walls close to the rear edges thereof, a shelf pivoted on said trunnions for supporting toothbrushes, a pair of blocks secured one to each of said side walls to support the forward portion of said shelf, a

spring tensioning said shelf against said blocks, an agitator mounted on said door adjacent its free vertical edge and having a serrated upper edge, and a tooth depending from the under side of said shelf and engaging the serrated upper edge of said agitator to cause the shelf to be oscillated against the action of said spring when said door is opened and closed.

7. A wall cabinet for toothbrushes, comprising 10 a cabinet body having spaced side walls and an open front side, a door hinged to one of said side walls to swing on a vertical axis for closing the open front side, a pair of end aligned trunnions journaled one in each of said side walls close 15 to the rear edges thereof, a shelf pivoted on said trunnions for supporting toothbrushes, a pair of blocks secured one to each of said side walls to support the forward portion of said shelf, a spring tensioning said shelf against said blocks, 20 an agitator mounted on said door adjacent its free vertical edge and having a serrated upper edge, and a tooth depending from the under side of said shelf and engaging the serrated upper edge of said agitator to cause the shelf to be oscillated against the action of said spring when 25 said door is opened and closed, said agitator being pivotally mounted on said door to be turned to a position in which its serrated top edge is out of alignment with said tooth.
